Primary Examiner—Clare E. Heflin

(57) **CLAIM**

The ornamental design for a chandelier, as shown and described.

DESCRIPTION

FIG. 1 is a perspective view thereof;
FIG. 2 is a front elevational view thereof;
FIG. 3 is a right side view, the left side view being a mirror image;
FIG. 4 is a back plan view thereof;
FIG. 5 is a top plan view thereof; and,
FIG. 6 is a bottom plan view thereof.

The broken line showing of environmental structure in FIGS. 1-6 is for illustrative purposes only and forms no part of the claimed design.
